UNITED STATES PATENT OFFICE.

JAMES RENSFORD FREELAND, OF WELLSVILLE, NEW YORK.

CARRIAGE-POLE.

SPECIFICATION forming part of Letters Patent No. 415,101, dated November 12, 1889.

Application filed May 18, 1889. Serial No. 311,284. (No model.)

To all whom it may concern:

Be it known that I, JAMES RENSFORD FREELAND, a citizen of the United States, and a resident of Wellsville, in the county of Allegany 5 and State of New York, have invented certain new and useful Improvements in Devices for Adjusting Carriage-Poles; and I do hereby declare that the following is a full, clear, and exact description of the invention, which 10 will enable others skilled in the art to which it appertains to make and use the same.

This invention relates to carriage and buggy poles.

The object is to produce an adjustable stub 15 or pole-eye by means of which a carriage or buggy pole may be adjusted to fit any size vehicle desired, and which shall be simple of construction, efficient and durable in use, and comparatively inexpensive of production.

With these objects in view, the invention 20 consists in the improved construction and combination of parts of a stub or pole-eye, as will be hereinafter fully described in the specification, illustrated in the drawings, and 25 pointed out in the claim.

In the accompanying drawings, forming part 30 of this specification, and in which like letters and figures of reference indicate corresponding parts, Figure 1 is a perspective view of a portion of a carriage-pole, showing my improved stub or pole-eye in place thereon. Fig. 31 is a detail view of a pole-eye, showing a series of openings therein; and Fig. 3 is a similar view of the same, showing a series of longitudinal slots.

Referring to the drawings, A designates the pole of a carriage, and B the circle or bow. As these parts are of the ordinary construction, it is not necessary to enter into a detailed 40 description of the same. Upon the inner side of the circle is secured my improved stub or pole-eye, which, as will be seen, is provided with a series of holes or slots 1, which are by preference about half an inch apart; but in 45 practice the distance will be regulated by the requirements of the case. This pole-eye is held in place upon the circle by means of bolts 2, which extend through the braces 3, connecting with the pole, and are provided 50 with nuts 4, by means of which the said pole-

eye is rigidly clamped in place. In adjusting this pole-eye to various size vehicles it is only necessary to loosen the nuts 4, remove the pole-eye, and insert the bolts through any of the openings, which will bring it to the desired position, and to replace the nut, when it will be held in place.

My device will be found especially advantageous where it is desired to construct light carriages, and where, as is often the case, it is 60 desired to combine considerable strength with a light appearance. The circle or bow may be reduced to a minimum at the ends, inasmuch as it is supported on one side by the brace and on the other side by the strap portion of the pole-eye. It should be borne in mind that a much greater strength is obtained with the same weight of wood and iron by this arrangement than where the strap portion of the pole-eye is fastened outside or 70 under the bow and vertical bolts are employed. This strap portion may, moreover, have considerable width and yet present a light appearance, as it rests edge up, and it is but slightly weakened by the series of holes.

Especial attention is directed to the fact 75 that by the arrangement of brace 3, bow B, and the pole-eye herein shown the ends of the bow are not only in a manner inclosed and firmly supported by said brace and the 80 strap portion of the pole-eye, but both the brace and pole-eye have a bearing-surface against wood, and are thus far less likely to become loosened by the strain and jar in using. This is especially desirable where an 85 attachment is to be shifted from time to time.

As before stated, instead of the holes slots 90 may be used, and in that event it will be only necessary to loosen the nut and slip the pole-eye either in or out until it is in the desired position.

It will thus be seen that although this device is exceedingly simple of construction, it will be found of the highest efficiency and durability in use, and may be attached to 95 any carriage or buggy pole at a small expense.

Having thus fully described my invention, what I claim as new, and desire to secure by Letters Patent, is—

The combination, in a carriage-pole, of the 100

to and in connection with said braces 3; circle or bow B, adjustable pole
spreader, having two eyes having their upper ends forming straps,
said bow being adapted to rest
between the rear end of said brace and said
strap and having perforations registering with
the perforations of the brace, said straps having
series of perforations, any pair of which
are adapted to register with the perforations
of the braces and straps, and the nutted
bolts adapted to pass through the registering

perforations of the braces, bow, and straps,
substantially as and for the purpose set forth.

In testimony that I claim the foregoing as
my own I have hereunto affixed my signature
in presence of two witnesses.

JAMES RENSFORD FREELAND.
